UNITED STATES PATENT OFFICE.

WILLIAM J. HAGMAN, OF PHILADELPHIA, PENNSYLVANIA, ASSIGNOR TO NILESBEMENT-POND COMPANY, OF NEW YORK, N. Y., A CORPORATION OF NEW JERSEY.

SLOTTING MACHINE.

Application filed June 27, 1921. Serial No. 480,841.

To all whom it may concern:

Be it known that I, WILLIAM J. HAGMAN, a citizen of the United States, residing at Philadelphia, in the county of Philadelphia and State of Pennsylvania, have invented 5 certain new and useful Improvements in Slotting Machines, of which the following is a specification.

This invention relates to machine tools 10 and particularly to slotters, millers and like machines of the general type wherein the work support comprises a work table rotatably supported on a transversely movable slide in turn supported on a saddle 15 longitudinally movable on the bed of the machine, the tool being mounted on a column and extending over the table.

The principal object of the invention is 20 to provide an improved machine of the general type stated wherein the mechanism for operating the work supporting elements is removed from a position likely to interfere with the operator, means being provided however at the hand of the operator 25 for controlling such mechanism.

It is an object of the invention to provide 30 in connection with the machine and the means for feeding the work supports, means for traversing the supports continuously, the feeding and traversing means preferably 35 operating through the same driving mechanism to move the supports.

Another object of the invention is to provide 35 in combination with the slotter cutter bar and the means for varying the stroke of the same, improved means for directly indicating the stroke to which the first means is adjusted.

With these and other objects in view, my 40 invention consists in the features of construction and operation set forth in the following specification and illustrated in the accompanying drawings. In such drawings annexed hereto and forming a part of this 45 specification, I have shown my invention embodied in a vertical crank slotter but it will be understood that the invention can be otherwise embodied and that the drawings are not to be construed as defining or 50 limiting the scope of the invention, the claims appended to this specification being relied upon for that purpose.

Referring to the figures of the drawings:

Figure 1 is a front elevation of a vertical crank slotter having the invention embodied therein.

Fig. 2 is a fragmentary rear elevation of the machine, portions thereof being shown in section.

Fig. 3 is a fragmentary front end elevation of the machine.

Fig. 4 is a plan view of the lower portion of the machine, parts thereof being shown in section.

Fig. 5 is a fragmentary sectional plan view taken on line 5—5 of Fig. 2.

Fig. 6 is an enlarged front elevation of the crank mechanism for reciprocating the cutter bar.

Fig. 7 is a sectional view thereof taken on line 7—7 of Fig. 6.

Fig. 8 is an enlarged elevation of a scale plate and pointer for indicating the stroke of the cutter bar.

Fig. 9 is a fragmentary sectional view thereof taken on the line 9—9 of Fig. 8.

In slotters, vertical milling machines and other machines of the general type defined above, means is ordinarily provided for either rotating the table or moving the same 80 rectilinearly. This means commonly comprises a plurality of shafts extending transversely of the machine and provided with change gears at the ends thereof projecting outwardly to a position at the front of the 85 machine directly in the path of the operator.

The provision of such construction permits quick and easy change of the gears whereby the table may be rotated or moved 90 rectilinearly but such arrangement forms an obstacle directly in the place where the operator normally would stand in attending the machine.

The present invention, among other improvements, provides means whereby the gearing is placed at the rear of the 95 machine entirely out of the path of the operator, means being provided however whereby the operator may control the same from his usual position at the front of the machine.

In the drawings, I have illustrated 100 such controlling means as comprising clutches operated from clutch rods extending to the front of the machine. It will be understood, however, that the drawings herein are merely illustrative and that 105 the invention is not to be limited to the de-

tails shown therein. Other improvements comprising the invention and the specific mechanism illustrated in the drawings will now be described.

5 In the drawings, 1 indicates the bed and 2 the upright or column of a vertical crank slotter. A cutter bar 3 counter-balanced at 4 and operated from a motor 5 is guided for vertical reciprocation in the upright. Bolts 10 6^a are provided for securing a tool or tools to the tool head 6 and the bar guide 7 may be adjusted vertically on the column by means of a screw 7^a. The cutter bar and head are vertically reciprocated from the 15 motor 5 through gears 8, 9, 10, driving connections at 11, shaft 12, crank 13, and a link 14 operatively connected to the cutter bar at 15.

Means is provided in connection with the 20 crank 13 for varying the stroke of the cutter bar 3 and further and improved means is also preferably provided for indicating the length of the stroke of the cutter bar for the various adjustments of the crank mechanism. This mechanism comprises the crank disk 13 on the inner end of shaft 12. A driver 16 connected to the link 14 is mounted to slide radially in a guideway 17 in the disk. A screw 18 is journaled radially in 30 the disk at 19 and is threaded at 20 to engage the driver. The screw is also preferably provided with a second finer thread 21 engaged by a threaded block 22 provided with a pointer 23 thereon adapted to move 35 along a scale 24 secured to the disk. It will be noted that the pitch of the threads are such that the driver and pointer move simultaneously as the screw is rotated, the arrangement being such that the pointer indicates directly on the scale the stroke imparted to the cutter bar 3 and head 6 for any 40 adjustment of the crank mechanism. The screw is held against longitudinal movement in the disk by means of a collar 25 and a nut 45 25^a thereon and may be rotated from a squared end portion 26 thereon.

The work support comprises a saddle 27 slidable longitudinally on ways 28 of the bed 1, a slide 29 transversely slidable on ways 50 30 of the saddle, and a work table 31 rotatably mounted on the slide. The saddle and slide are moved respectively by means of screws 32 and 33. The table is rotated from a shaft 34 having a worm 35 splined thereto and meshing with a worm wheel 36 on the work table. The screw shaft 33 and shaft 55 34 extend rearwardly parallel with the ways 30 on the saddle into a gear box 37^a mounted on the saddle. The forward ends of 60 shafts 33 and 34 are squared at 33^a and 34^a respectively whereby the same may be rotated by hand for fine adjustments. Shaft 33 may also be rotated from the squared ends of a shaft 33^b connected to shaft 33 65 through spiral gears 33^c. Gears 37 and 38

driven from a gear 36^a on a shaft 39 are loosely mounted respectively on shafts 33 and 34 within the gear box. Clutches 40 and 41 splined to shafts 33 and 34 are adapted to operatively connect either gear with 70 its shaft. A yoke 42 engaging the clutches at its ends and pivoted at 43 is adapted to be operated by a clutch rod 44 pivoted to one end of the yoke at 44^a and extending to the front of the machine whereby either 75 shaft 33 or 34 may be thrown into operation to move the slide or to rotate the table. The shaft 39 carries a bevel gear 45 at its inner end which meshes with a like gear 46 splined to a shaft 47. Shaft 39 and gears 45 and 46 are rotatably supported on the saddle and move therewith along the shaft 47.

The feeding of the work supporting elements is preferably accomplished from the tool operating means as follows: A shaft 48 85 is oscillated from a cam 49 on shaft 12 through a lever 50 mounted on one end of the shaft and engaging the cam. A second lever 51 on the forward end of shaft 48 is operatively connected by a link 52 to a disk 90 53. The disk 53 is loosely mounted on the hub of a gear 54 keyed to a shaft 55 mounted in the bed. The shaft 55 is operatively connected to the shaft 47 through bevel gears 56 and 57 secured to such shafts respectively. Gear 54 is operatively connected to the saddle screw 32 through a gear 58 keyed to a shaft 59, bevel gears 60 and 61 on shaft 59 and screw 32 respectively, and a clutch 62 splined to shaft 59. The gear 60 is loosely mounted on the shaft 59 and is connected thereto by means of the clutch 62. Gear 58 meshes directly with gear 54. In operation the oscillation of shaft 48 is transmitted to the disk 53 and from thence to the gear 54 and shaft 55 through a ratchet pawl mechanism 63 mounted on the disk and adapted to engage the teeth of gear 54 to drive the same intermittently in one direction. A handle 64 is provided on the pawl mechanism whereby the same may be held 100 out of driving engagement relative to the gear 54 or may place the pawl mechanism to drive the gear 54 in either direction. A clutch rod 65 has a yoke 66 thereon engaging the clutch 62 whereby the clutch may be shifted into or out of engagement with the bevel gear 60 which is loose on shaft 58.

The operation of the feed mechanism is 115 as follows: To feed the saddle 27 the clutch 62 is placed in engagement with gear 60. The oscillation of the disk 53 will thus be transmitted to the screw 32 to feed the saddle. When it is desired to feed the slide 29 or to rotate the table 31, the clutch 62 is disengaged from gear 60. The oscillations of disk 53 are transmitted through shaft 55 and the other mechanism described to the gears 37 and 38 on the screw shaft 33 and 120 table operating shaft 34. The clutch yoke 125

42 may be operated from the rod 44 to engage either clutch 40 or 41 with its gear and thereby drive either the screw shaft 33 or shaft 34 as desired. The slide is thereby 5 moved on its ways and the table rotated from these shafts as heretofore described.

Means comprising a gear 67 loosely mounted on shaft 47 is also preferably provided for continuously operating the saddle, slide and table shafts to effect traversing movement of the saddle, slide and table. I have illustrated a motor 68 for performing this function, gears 69, 70, shaft 71 and gear 72 providing an operative connection from the 10 motor to the gear 67 which gear may be operated continuously therefrom when desired. A clutch 73 splined to shaft 47 is adapted to be engaged with gear 67 to operate the shaft 47 from the motor 68 when desired. 15 A clutch rod 74 engages an arm 75^a of a clutch yoke 75 in engagement with clutch 73 whereby the clutch may be shifted into or out of engagement with gear 67. During this traversing operation, the pawl mechanism 63 is held in a neutral position.

What I claim is:

1. In a machine tool, the combination comprising a table, a slide for supporting said table, a set of gearing for operating said slide and for rotating said table, means comprising a unitary member for selectively connecting said gearing to the slide and to said table, and means for selectively operating said gearing intermittently and continuously.

2. In a machine tool, the combination comprising a table, a transversely movable slide for supporting said table, a set of gearing located at the rear of the machine for operating said slide and for rotating said table, means controlled from the front of the machine for selectively connecting said gearing to the slide and to the table, and means for operating said gearing to effect intermittent feeding movement of the slide and intermittent rotation of the table and means to effect continuous movement of the slide and continuous rotation of the table.

3. In a machine tool, the combination comprising a table, a slide for supporting said table, a set of gearing located at the rear of the machine for operating said slide and for rotating said table, means comprising a rod extending from said gearing to the front of the machine for selectively connecting said gearing to the slide and the table, and means for selectively operating said gearing intermittently and continuously.

4. In a machine tool, the combination comprising a table, a transversely movable slide for supporting the table, a longitudinally movable saddle for supporting said slide, means comprising a set of gearing located 55 at the rear of the machine and controlled

from the front thereof for intermittently feeding said slide and for intermittently rotating said table, and means for operating said gearing to traverse said slide and to continuously rotate said table.

5. In a machine tool, the combination comprising a table, a slide for supporting said table, a set of gearing, two clutches for connecting said gearing to operate said slide and to rotate said table, means comprising a unitary member for operating said clutches to selectively connect the gearing to the slide and the table, and means for selectively operating said gearing intermittently and continuously.

6. In a machine tool, the combination comprising a table, a slide for supporting said table, a set of gearing located at the rear of the machine, two clutches adapted to connect said gearing to operate said slide and to rotate said table, and means comprising a rod extending from the rear of the machine to the front thereof for operating said clutches to selectively connect the gearing to the slide and the table.

7. In a machine tool, the combination comprising a table, a slide for supporting said table, a set of gearing located at the rear of the machine, two clutches for connecting said gearing to operate said slide and to rotate said table, means comprising a rod extending from the rear of the machine to the front thereof for operating said clutches to selectively connect the gearing to the slide and the table, and means for selectively operating said gearing intermittently and continuously.

8. In a machine tool, the combination comprising a table, a slide for supporting said table, a set of gearing located at the rear of the machine, two clutches for connecting said gearing to operate said slide and to rotate said table, a yoke member for operating said clutches, and means comprising a rod extending from the rear of the machine to the front thereof for operating said yoke member to selectively connect the gearing to the slide and the table.

9. In a machine tool, the combination comprising a work table, a shaft for effecting rotative movement of the table, a second shaft for effecting linear movement of the table, a set of gearing located at the rear of the machine for operating said shafts, and means comprising a rod extending from said gearing to the front of the machine for selectively connecting said gearing to said shafts.

10. In a machine tool, the combination comprising a work table, a shaft for effecting rotative movement of the table, a second shaft for effecting linear movement of the table, a set of gearing located at the rear of the machine for operating said shafts, means comprising a rod extending from said gearing to the front of the machine for selectively connecting said gearing to said shafts.

tively connecting said gearing to said shafts, and means for selectively operating said gearing intermittently and continuously.

11. In a machine tool, the combination comprising a work table, a shaft for effecting rotative movement of the table, a second shaft for effecting linear movement of the table, a set of gearing located at the rear of the machine, two clutches for connecting said gearing to said shafts, a yoke member for operating said clutches, and means comprising a rod extending from the rear to the front of the machine for operating said yoke member to selectively effect operation of said shafts.

12. In a machine tool, the combination comprising a work table, a shaft for effecting rotative movement of the table, a second shaft for effecting linear movement of the table, a set of gearing located at the rear of the machine, two clutches for connecting said gearing to said shafts, a yoke member for operating said clutches, means comprising a rod extending from the rear to the front of the machine for operating said yoke member to selectively effect operation of said shafts, and means for selectively operating said gearing intermittently and continuously.

13. A machine tool comprising the combination of a bed, an upright thereon, tool supporting means on the upright, tool operating means, a saddle longitudinally slidable on the bed, a slide transversely slidable on the saddle, a work table rotatably mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means for operating the saddle screw and the said gearing for feeding the saddle, slide and table, and means extending from the said gearing to the front of the machine for selectively connecting the second screw and the shaft with the feeding means.

14. A machine tool comprising the combination of a bed, an upright thereon, tool supporting means on the upright, tool operating means, a saddle longitudinally slidable on the bed, a slide transversely slidable on the saddle, a work table rotatably mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means for operating the saddle screw and the said gearing for feeding the saddle, slide and table, a clutch operating rod extending from the said gearing to the

front of the machine for selectively connecting the second screw and the shaft with the feeding means, and means at the front of the machine for connecting the saddle screw with the said feeding means.

15. A machine tool comprising the combination of a bed, an upright thereon, tool supporting means on the upright, tool operating means, a saddle longitudinally slidable on the bed, a slide transversely slidable on the saddle, a work table rotatably mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means for operating the saddle screw and the said gearing for feeding the saddle, slide and table, a clutch operating rod extending from the said gearing to the front of the machine for selectively connecting the second screw and the shaft with the feeding means, means at the front of the machine for connecting the saddle screw with the feeding means, and means whereby the saddle and slide may be traversed and the table continuously rotated.

16. A machine tool comprising the combination of a bed, an upright thereon, tool supporting means on the upright, tool operating means, a saddle longitudinally slidable on the bed, a slide transversely slidable on the saddle, a work table rotatably mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means for operating the saddle screw and the said gearing for feeding the saddle, slide and table, a clutch element on the second screw, a clutch element on the shaft, pivoted means operatively connected to each clutch element, a rod connected to the pivoted means and extending to the front of the machine whereby the operator may connect either the second screw or the shaft with the feeding means, means at the front of the machine for connecting the saddle screw with the feeding means and means operative through the feeding connections whereby the saddle and slide may be traversed and the table continuously rotated.

17. A machine tool comprising the combination of a bed, an upright thereon, tool supporting means on the upright, tool operating means, a saddle longitudinally slidable on the bed, a slide transversely slidable on the saddle, a work table rotatably mounted on the slide, a screw for moving the saddle longitudinally, a second screw for moving

the slide transversely, a shaft extending parallel with the said second screw and operatively connected to the table for rotating the same, a second shaft extending parallel with the bed, means including gearing for operatively connecting the second shaft with the bed, means for operating the second shaft intermittently and continuously, and means comprising a unitary member at the front of the machine for selectively connecting the second screw and the first shaft with the second shaft.

5 mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means including the said gearing for operatively connecting the shaft and screws with the said power means for feeding the saddle, slide and table, a clutch operating rod extending from the said gearing to the front of the machine for selectively connecting the second screw and the shaft.

18. A slotter comprising the combination of a bed, an upright thereon, a tool support head mounted for vertical reciprocation on the upright, power means for reciprocating the head, a saddle longitudinally slideable on the bed, a slide transversely slideable on the saddle, a work table rotatably mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means including the said gearing for operatively connecting the shaft and screws with the said power means for feeding the saddle, slide and table, and means extending from the said gearing to the front of the machine for selectively connecting the second screw and the shaft with the feeding means.

19. A slotter comprising the combination of a bed, an upright thereon, a tool support head mounted for vertical reciprocation on the upright, power means for reciprocating the head, a saddle longitudinally slideable on the bed, a slide transversely slideable on the saddle, a work table rotatably mounted on the slide, a screw for moving the saddle longitudinally, a second screw for moving the slide transversely, a shaft extending parallel with the said second screw and operatively connected to the table for rotating the same, a second shaft extending parallel with the first shaft, gearing at the rear of the machine for operatively connecting the second shaft with the first shaft and second screw, a third shaft extending parallel with the bed and operatively connected with the second shaft, means for operating the third shaft intermittently and continuously, and means extending from the said gearing to the front of the machine for selectively connecting the second screw and the first shaft with the feeding means.

20. A slotter comprising the combination of a bed, an upright thereon, a tool support head mounted for vertical reciprocation on the upright, power means for reciprocating the head, a saddle longitudinally slideable on the bed, a slide transversely slideable on the saddle, a work table rotatably mounted on the slide, a screw for moving the saddle longitudinally, a second screw for moving the slide transversely, a shaft extending parallel with the said second screw and operatively connected to the table for rotating the same, gearing at the rear of the machine for operating the shaft and second screw, means including the said gearing for operatively connecting the shaft and screws with the said power means for feeding the saddle, slide and table, a clutch operating rod extending from the said gearing to the front of the machine for selectively connecting the second screw and the shaft with the feeding means, and means at the front of the machine for connecting the saddle screw with the said feeding means.

25 30 35 40 45 50 55 60 65 70 75 80 85 90 95 100 105 110 115 120 125 130

22. A slotter comprising the combination of a bed, an upright thereon, a tool support head mounted for vertical reciprocation on the upright, power means for reciprocating the head, a saddle longitudinally slideable on the bed, a slide transversely slideable on the saddle, a work table rotatably mounted on the slide, a screw for moving the saddle longitudinally, a second screw for moving the slide transversely, a shaft extending parallel with the said second screw and operatively connected to the table for rotating the same, a second shaft extending parallel with the bed, means including gearing for operatively connecting the second shaft with the first named shaft and second screw, means for operating the second shaft intermittently from the said power means, means for operating the second shaft continuously, clutch means operative from the front of the machine for

connecting either of such means to the second shaft, and means comprising a unitary member at the front of the machine for selectively connecting the second screw 5 and the first shaft with the second shaft.

23. A slotter comprising the combination of a bed, an upright thereon, a tool supporting head mounted for vertical reciprocation on the upright, an electric motor for reciprocating the head, a saddle longitudinally slidable on the bed, a slide transversely slidable on the saddle, a work table rotatably mounted on the slide, a screw for moving the saddle longitudinally, a second screw for 10 moving the slide transversely, a shaft extending parallel with the said second screw and operatively connected to the table for rotating the same, a second shaft extending parallel with the bed, means including gearing for operatively connecting the second shaft with the first named shaft and second screw, a second electric motor, means operative between one of the motors and the second shaft for operating the same intermittently synchronously with the reciprocation of the head, means whereby the second shaft 15 may be operated continuously from the second motor, and means at the front of the machine whereby the operator may connect 20 either the second screw or the first shaft with the second shaft.

24. A stroke indicator comprising the combination of a rotary element, a screw mounted radially therein, a driver mounted 35 in the element in threaded engagement with the screw and adapted to be adjusted radially of the element as the screw is rotated, a stroke indicating element in threaded engagement with the screw, and a scale along 40 which the indicating element is adapted to travel as the screw is rotated.

25. A stroke indicator comprising the combination of a rotary element, a screw mounted radially therein and having relatively 45 fine and coarse threads cut respectively therein on different portions of its length, a driver mounted in the element in engagement with the coarse thread and adapted to be adjusted radially of the element as the 50 screw is rotated, a stroke indicating element in threaded engagement with the fine thread of the screw, and a scale along which the

indicating element is adapted to travel as the screw is rotated.

26. A stroke indicator comprising the 55 combination of a rotary element, a screw journaled radially therein, the screw having a fine thread cut therein adjacent the journaled portion thereof and a relatively coarse thread cut on another portion thereof, a 60 driver mounted in the element in engagement with the coarse thread and adapted to be adjusted radially of the element as the screw is rotated, a stroke indicating element in threaded engagement with the fine thread 65 and adapted to slide radially in the journaled portion of the rotary element, and a scale on the rotary element along which the indicating element is adapted to travel as the screw is rotated. 70

27. In a slotter, the combination of a reciprocatory tool head, a rotary element, a driver mounted in the rotary element and operatively connected to the head to reciprocate the same, means on the rotary element 75 engaging the driver and adapted to adjust the driver radially of the rotary element to vary the stroke of the head, stroke indicating means comprising a pointer connected to the first named means and movable on 80 the rotary element, and a scale on the rotary element along which the pointer is adapted to travel, the several parts being so related that the pointer definitely indicates the rectilinear stroke of the head on the scale. 85

28. In a slotter, the combination of a reciprocatory tool head, a rotary element, a driver mounted in the rotary element and operatively connected to the head, a screw 90 rotatably and radially mounted in the rotary element in threaded engagement with the driver for adjusting the same radially of the rotary element to vary the stroke of the head, a scale indicating means threadedly engaging the screw and comprising a 95 pointer, and a scale on the rotary element along which the pointer is adapted to travel as the screw is rotated, the several parts being so related that the pointer definitely indicates the rectilinear stroke of the head on 100 the scale.

In testimony whereof, I hereto affix my signature.

WILLIAM J. HAGMAN.
